RICHARD TJADER, OF NEW YORK, N. Y.

RELEASING APPARATUS FOR LIFE-BOATS.

1,159,293.

Specification of Letters Patent.

Patented Nov. 2, 1915.

Application filed March 28, 1914. Serial No. 827,855.

To all whom it may concern:

Be it known that I, RICHARD TJADER, a citizen of the United States, and a resident of the city of New York, borough of Manhattan, in the county and State of New York, have invented a new and Improved Releasing Apparatus for Life-Boats, of which the following is a full, clear, and exact description.

10 This invention relates to ships, and has particular reference to apparatus for manipulating lifeboats from the decks of ships.

More definitely stated, among the objects of the invention is to improve the means for 15 releasing a lifeboat from the ropes or cables associated with the davits after the boat approaches or reaches the water.

A further object of the invention is to generally improve the connections between 20 the davit apparatus and the lifeboat whereby the connections are made safer than devices commonly employed for these purposes and also whereby the manipulation of 25 the connecting devices is made both easier and more reliable than heretofore.

The foregoing and other objects of the invention will hereinafter be more fully described and claimed and illustrated in the drawings forming a part of this specification 30 in which like characters of reference indicate corresponding parts in all the views, and in which—

Figure 1 is a vertical longitudinal section of a lifeboat embodying my improvement in 35 its preferred form: Fig. 2 is a similar view of one end of the lifeboat on a larger scale; Fig. 3 is a vertical section on the line 3—3 of Fig. 2; and Fig. 4 is a detail view of one 40 of the devices for locking the supporting hooks in normal position.

The several parts of the device may be 45 made of any suitable materials, and the relative sizes and proportions, as well as the general design of the mechanism, may be varied to a considerable extent without departing from the spirit of the invention hereinafter more fully set forth and specifically claimed.

Referring more particularly to the drawings I show at 10 a conventional form of 50 lifeboat having at its bow and stern pivoted hooks 11 and 12, each pivoted on a fixed pivot 13 and constituting a part of or secured to a metal rod or brace 14 extending upwardly from the keel 15. Each hook constitutes a lever of the second class, and is so

arranged that the long arm thereof swings around the pivot 13 in a substantially vertical plane and toward the opposite end of the boat. The ends or points of the hooks 50 extend downwardly through the top plates 16 and 17 of bulkheads 18 and 19 at the bow and the stern of the boat respectively.

Secured to each of the bulkheads in any suitable manner, preferably to the top plate 65 16 or 17 thereof, is a bracket 20 shown as secured rigidly by means of a horizontal flange 21 to said plate. To the bracket is secured in any suitable manner a rigid guide 70 22 which may be of any suitable form or nature, but shown herein as being a tubular member having a notch or recess 23 at its upper end as shown at Figs. 2 and 4. At the lower end of the guide is a flange or shoulder 24, and slidable along or within the 75 guide is a keeper 25 having a hollow or tubular head 26 at its upper end adjacent the notch 23 and a stem 27 extending downwardly from the head through or along the shoulder 24. A spring 28 surrounds the 80 stem within the guide. The stem has a normal tendency to maintain the head 26 of the keeper projected upwardly along the side of or above the notch 23 of the guide. The position and form of the bracket and the parts 85 just described associated therewith are such that the end of the hook will strike against the wall of the guide opposite the notch as it swings downwardly around its pivot 13 when the keeper is drawn downwardly, and 90 when the keeper is moved to normal position by its spring, the head 26 thereof will embrace the point of the hook.

Any suitable means may be provided for manipulating the keepers to withdraw them 95 simultaneously from the hooks, allowing the hooks to swing upwardly on their pivots and thereby detaching or releasing the lifeboat from the davit connections. The means I prefer to employ for this purpose includes a 100 cable or line 29 connected at one end to one of the stems 27 and extending thence to the stem of the other keeper where it is securely connected. A turn buckle 30 located at any desired place or point between the ends of the cable may be employed to maintain the 105 cable under proper tension. When the shackles are being replaced upon the hooks 11 and 12 to reconnect the lifeboat to the davits, the hooks may gravitate to and lie 110 against the outsides of the keepers, and when the keepers are retracted as herein set forth

into or along the guides 22, the points of the hooks will drop into position to be engaged by the keepers when they return to normal position.

5 Located preferably in the bulkhead 18 at the stern of the boat is the actuating mechanism for operating the keepers 25. This actuating mechanism comprises preferably a pair of pulleys 31 journaled on fixed axes 32 10 extending horizontally in the same plane between a pair of side plates 33 arranged in vertical parallel planes. The plates 33 are slotted, as indicated at 34, and a movable pulley 35 is movable vertically between said 15 plates and preferably has its axes 36 projecting into or through said slots 34 whereby the movable pulley is maintained with its axis in a plane substantially midway between the plane of the axis 32 of the fixed pulleys and 20 providing for movement of the pulley 35 upwardly from the horizontal plane of the axes 32. The intermediate portion of the cable 29 passes under the pulleys 31 and in a loop over the pulley 35. Connected to the 25 pivot 36 of the movable pulley is a yoke or pair of links 37, and a rod 38 leads from the links 37 upwardly through the plate 17 of the rear bulkhead, terminating preferably in a loop or eye 39. The eye portion of the 30 rod 38 rests normally in a pocket 17' of said plate 17 where it may be engaged by any suitable means as by means of a lever hook 40 for drawing upwardly on the movable pulley. Since the cable 29 is maintained 35 substantially taut by virtue of the turn buckle and the springs 27, there will be no danger of the displacement of the cable from the pulleys nor likelihood that the pulley 35 will deviate from the vertical fore and aft 40 plane illustrated. Hence, the eye 39 will always be maintained in substantially the same normal position ready for engagement by the hook or other means for lifting upon the rod 38. By providing a hook lever of 45 the character shown at 40 for manipulating the movable pulley as herein set forth, there is no likelihood that any occupant of the boat may cause the boat to be released prematurely. The officer put in command of 50 the lifeboat will, of course, understand how to use the releasing apparatus and may do so readily at the proper time.

From the description of the mechanism herein given it will follow that any authorized person drawing upwardly upon the loose pulley 35 may retract the keepers 25, drawing them against the tension of the springs 28, and both of the keepers will be operated substantially simultaneously, allowing both hooks to swing free at the same time. If, by reason of slightly increased friction between the cable 29 and parts of the boat between the actuating mechanism and the bow of the boat, the spring 28 at 65 the stern may be slightly heavier than the

one at the bow, but in any event the movement of either keeper, sufficient to release its hook, cannot be so great but that such keeper will constitute a positive abutment insuring that the draft upon the movable pulley will 70 certainly release the opposite keeper.

By the use of my improved lifeboat launching devices, it is possible and practical for a lifeboat to be launched and manipulated from a ship while the ship is in full speed, making it possible, for instance, for a rescue to be effected in much less time than would be required to first stop or turn the ship. 75

Having thus described my invention, I 80 claim as new and desire to secure by Letters Patent:—

1. In a lifeboat releasing apparatus, the combination with a lifeboat and a pair of hooks pivoted thereto and having their 85 points projecting downwardly and inwardly toward the center of the boat, of a pair of spring pressed slidable keepers serving normally to hold the points of the hooks in locking position, tubular guiding means confining the movement of the keepers in straight lines, a cable extending from one keeper to the other, a series of direction pulleys mounted on fixed axes between the keepers and coöperating with the cable, a movable pulley 95 arranged in a loop of the cable between its ends, and means to draw the movable pulley away from the plane of the fixed pulley axes to cause tension to be applied through the cable upon the keepers simultaneously to 100 withdraw them from the points of the hooks.

2. In lifeboat releasing apparatus, the combination with a lifeboat and a pair of hooks pivotally connected at the bow and stern thereof, of a pair of brackets secured 105 adjacent said hooks, each bracket having associated therewith a tubular guide, a keeper having a hollow head adapted to reciprocate in said guide, a spring acting upon the keeper serving to normally project it above the 110 guide into position to engage the point of the hook, a cable extending from one keeper to the other, and actuating means coöperating with a loop of the cable between the keepers and applying such tension to the 115 cable as will release both keepers from their hooks simultaneously against the tension of said springs.

3. The combination with a lifeboat and a pair of hooks connected to the bow and stern 120 thereof respectively, of a bracket fixed in position adjacent each hook, each bracket having a tubular guide provided at its upper end with a notch, a keeper movable in said guide and coöperating with the adjacent 125 hook when in normal position, each keeper comprising a tubular member adapted to telescope over the point of the hook after said point has passed through said notch, a spring acting between one end of the guide 130

and said keeper tending to hold the keeper in engaging position at all times, actuating means adjacent the stern hook, and a cable extending from one keeper to the other and 5 over said actuating means, the keeper spring adjacent the actuating means being heavier than the other.

4. In releasing apparatus for lifeboats, the combination with a lifeboat and movable 10 engaging members connected thereto at the stern and bow, of a bracket adjacent each movable member, means associated with the bracket to limit the downward movement of each member, a movable keeper coöperating 15 with the movable member and adapted to hold it in holding position, a flexible member extending from one keeper to the other, means acting upon the keepers to hold them

in engaging position, actuating means co-operating with said flexible member between 20 the keepers but adjacent the stern, a vertically extending rod leading from said loop and having an eye at its upper end, and a loose lever having a hook intermediate its 25 ends adapted to engage said eye for applying draft upon the flexible member for withdrawing both keepers simultaneously from engaging position.

In testimony whereof I have signed my name to this specification in the presence of 30 two subscribing witnesses.

RICHARD TJADER.
